United States Patent Office

Des. 228,411
Patented Sept. 18, 1973

228,411

WASTE RECEPTACLE

Lester Miller, St. Louis County, Mo., assignor to Contico International, Inc., St. Louis, Mo.

Filed Nov. 8, 1971, Ser. No. 196,860

Term of patent 14 years

Int. Cl. D7—07

U.S. Cl. D49—35

FIG. 1

FIG. 3

FIG. 2

FIG. 4

FIG. 1 is a front elevational view of a waste receptacle showing my new design.

FIG. 2 is a side elevational view thereof.

FIG. 3 is a top plan view thereof.

FIG. 4 is a bottom plan view thereof.

I claim:

The ornamental design for a waste receptacle, as shown.
